UNITED STATES PATENT OFFICE

CHARLES W. TODD, OF SCHENECTADY, NEW YORK

JOURNAL BEARING FOR RAILROAD VEHICLES

Application filed August 5, 1927. Serial No. 210,753.

This invention relates to bearings for the journals of locomotives and other railroad vehicles, and its object is to provide an appliance of such character, which will be of simple and inexpensive construction, ready applicability in standard practice, and operative to ensure the effective lubrication of the surfaces in contact.

The improvement claimed is hereinafter fully set forth.

In the accompanying drawing: Figure 1 is a side view, in elevation, of a portion of an electric locomotive, in which the invention is applied; Fig. 2, a vertical transverse section, on an enlarged scale through a journal bearing embodying the invention, in operative position in a journal box, taken on the line $\alpha\alpha$ of Fig. 3; Fig. 3, a plan or top view; Fig. 4, a transverse section, on the line $\alpha\alpha$ of Fig. 3, through the journal bearing, detached, and; Fig. 5, a vertical longitudinal section on the line yy of Figs. 3 and 4.

It has been found in practice, with the ordinary design of journal bearings, that the action of the axle of the vehicle on which it is applied, when in rotation, collects and delivers oil to the grooves in the bearing, which soon overflow, through the filling hole in the top, due to their limited capacity and direct connection to the filling-hole. The present invention is designed to eliminate this objection, by providing capacious cavities for the reception of oil, in the interior of the bearing.

In the practice of the invention, referring descriptively to the specific embodiment thereof which is herein exemplified, the journal bearing, which is indicated, as an entirety, by the reference numeral, 1, is fitted, as heretofore in a journal box, 2, having an oil cellar or sump, 3, located between its side walls, said oil cellar being fitted with oil soaked waste or packing, 3^a, and being open at its top to the journal, 4, of the vehicle axle.

The oil cellar is secured in position in the journal box, by transversely extending pins or bolts, 3^b. Oil is supplied to the journal bearing, at its top, through an oil conduit, 2^a, in the journal box.

The journal bearing, 1, is a hollow or

chambered casting, of rectangular form in longitudinal section and having an arcuate bottom, which may be faced with a liner, 1^a, of babbitt, or other suitable soft metal, curved to the radius of the axle journal. An oil reservoir is cored in the journal bearing, said reservoir preferably comprising, as shown, a plurality of compartments, 1^b, on each of its sides, said compartments being upwardly and inwardly curved, in substantial similarity to the bottom of the bearing; and having open tops, which are covered by a plate, 1^c, secured to the top of the bearing and closing the tops of the compartments thereat. Said compartments communicate, at their lower extremities, with each other and with the arcuate face of the bearing, through openings, 1^d, and longitudinal passages, 1^e. The superimposed load on the journal box is transferred, through the cover plate, 1^c, to the journal bearing, 1, and the end walls, and partition walls between the compartments of the journal bearing, constitute the vertical members which support this load. The compartments on the opposite sides of the journal bearing, communicate, through the middle rib thereof, by passages, 1^f, which allow oil to pass from each compartment on one side, to a corresponding compartment on the opposite side, and the oil supply is equalized and distributed through the compartments of each side, by the longitudinal passage, 1^g, of that side. Thus, oil rising in one of the compartments, due to the action of the axle, enters a cavity of large capacity, and if this is filled, will overflow through the communicating passage, 1^f, to the opposite side compartment. One of said passages, at the middle of the length of the bearing is open at top to the filling conduit 2^a, of the journal box, and oil overflowing from one side, passes to the opposite side without escaping through the filling conduit.

It will be seen that the invention provides a journal bearing, embodying an oil reservoir of ample capacity, which, while reducing the weight of the bearing, ensures the ample strength thereof. Further, as the large capacity of the interconnected compartments, prevents the escape of oil from

the box, through the filling conduit, effective lubrication is correspondingly promoted.

The invention claimed as new, and desired to be secured by Letters Patent, is:

5 1. In a device of the class described, the combination of a hollow journal bearing; and a journal box therefor, having oil filling means, whereby oil is supplied to the hollow of said bearing, the hollow being comprised of a plurality of chambers open to the journal, some only of which are out of communication with the said oil filling means, except indirectly through their said communication with the journal, whereby they receive surplus oil 10 therefrom for subsequent refeeding thereto.

15 2. In a device of the class described, the combination of a hollow journal bearing; and a journal box therefor, having oil filling means, whereby oil is supplied to the hollow of said bearing, the hollow being comprised of two longitudinal rows of chambers, one on each side of the vertical central plane of the journal, some only of said chambers being out of communication with the said oil 20 filling means, except indirectly through their said communication with the journal, whereby they receive surplus oil therefrom for subsequent refeeding thereto, each of said chambers of one row being in communication with 25 a corresponding chamber of the other row through an opening at the top of their separating wall, whereby one chamber may overflow into the other.

30 3. In a device of the character described, the combination of a journal box; a journal; and a hollow crown bearing interposed between the box and the journal, the said crown bearing comprising a longitudinal partition, a plurality of lubricant chambers on each side 35 of the partition, a plurality of passageways leading through the partition, each passageway establishing communication between one of the chambers on one side of the partition and one of the chambers on the other side of 40 the partition, and a passageway leading from each chamber to the journal.

45 4. In a device of the character described, the combination of a journal box; a journal; and a hollow crown bearing interposed between the box and the journal, the said crown bearing comprising a longitudinal partition, a plurality of chambers on each side of the partition, a plurality of grooves each open to the journal, a plurality of passageways leading 50 through the partition each passageway establishing communication between one of the chambers on one side of the partition and one of the chambers on the other side of the partition, and a passageway leading from each chamber to one of the grooves.

55 5. In a device of the character described, the combination of a journal box; a journal; and a hollow crown bearing interposed between the box and the journal, the said crown bearing comprising a longitudinal partition,

60 a plurality of chambers on each side of the partition, a plurality of grooves each open to the journal, a plurality of passageways leading through the partition each passageway establishing communication between one of the chambers on one side of the partition and one of the chambers on the other side of the partition, and a passageway leading from each chamber to one of the grooves, the said journal box having a passageway for lubricant in communication with one of the passageways in the partition.
